CLAIM

The ornamental design for a bra, as shown and described.

DESCRIPTION

FIG. 1 is a perspective view of a bra showing my new design; FIG. 2 is a front elevational view of the bra of FIG. 1 thereof; FIG. 3 is a rear view of the bra of FIG. 1 thereof; FIG. 4 is a left-side view of the bra of FIG. 1 thereof, wherein the right-side view is a mirror image of the left-side view thereof; FIG. 5 is a top view of the bra as shown in FIG. 1 thereof; and, FIG. 6 is a bottom view of the bra as shown in FIG. 1 thereof.

1 Claim, 6 Drawing Sheets
